(57) **CLAIM**

The ornamental design for an animate bearer portage device, as shown and described.

DESCRIPTION

FIG. 1 is a perspective view of an animate bearer portage device, showing our new design.

FIG. 2 is a front view thereof.

FIG. 3 is a right side view, the left side being a mirror image thereof.

FIG. 4 is rear view thereof.

FIG. 5 is a top view thereof; and,

FIG. 6 is a bottom view thereof.

The broken-line showing of environmental structure in FIGS. 1-6 is for illustrative purposes only and forms no part of the claimed design.
